SHOULDER BOARD OR SIMILAR ARTICLE

Franklin J. Stanton, Brooklyn, N. Y., assignor of
one-half to Arthur Stanton, Brooklyn, N. Y.

Application October 12, 1942, Serial No. 461,806

4 Claims.

(Cl. 2—246)

This invention relates to devices known as shoulder boards which are worn by naval officers on the shoulders of the jackets of their uniforms.

One object of the invention is the provision of a shoulder board which can be made in its entirety without the use of fabric or metal, which is light and yet of the proper stiffness, which is impervious to moisture and which is capable of retaining its shape indefinitely.

Another object of the invention is the provision of a shoulder board formed entirely or substantially entirely of a plastic.

A further object of the invention is to provide a shoulder board of such construction that the main or plate element thereof is formed in a single piece, without lamination or plying of stiffening and covering materials heretofore required in the manufacture of shoulder boards.

Another object of the invention is to provide a shoulder board or other article with an improved means for fastening the same in position.

A yet further object of the invention is generally to provide a shoulder board of improved construction, especially in respect to the simplicity of the construction and the durability thereof.

The above and other objects, features and advantages of the invention will be fully understood from the following description, reference being had to the accompanying illustrative drawing:

In the drawing:

Fig. 1 is a top view of a shoulder board embodying the present invention;

Fig. 2 is a bottom view thereof;

Fig. 3 is a sectional view on the line 3—3 of Fig. 2;

Fig. 4 is an edge view, mainly in elevation, and partly in section, of the shoulder board, showing the fastener member in released position;

Fig. 5 is a sectional view on the line 5—5 of Fig. 2;

Fig. 6 is a fragmentary view of one side of the fastening member;

Fig. 7 is a view, in elevation, of one end of the shoulder board, the fastening member being removed, as seen from the right of Fig. 2.

Referring now to the drawing in detail, the shoulder board 10 embodying the present invention is of such construction that it can be and is preferably formed of a plastic. Any of the well-known plastics can be used for making this shoulder board, for example, cellulose acetate, Bakelite, vinylite, etc. Said shoulder board comprises a plate 12 of the regulation size and shape.

Said plate 12 is formed of plastic and is of suitable thickness so that it is substantially stiff and can not be easily bent. The insignia elements 14, 16 and 18 are secured to the upper or front surface 20 of plate 12 and are also preferably formed of a plastic. Said insignia elements can be molded integrally with plate 12 or can be otherwise united therewith, for example, by forming said insignia elements as initially separate members which are subsequently adhesively secured to surface 20 of the plate in any suitable way. It will be understood that the adhesive securing may be provided by applying a solvent for the plastic material, for example, acetone when the plastic utilized is cellulose acetate. Plate 12 can be cut from a sheet of plastic and need not be molded as a separate element. It will be understood that the color of plate 12 is black, preferably a dull black, and that the outer surfaces of the insignia elements are of gold color.

The fastening means for shoulder board 10 is also preferably formed entirely of a plastic and comprises a shouldered stud 22 which is fixed to and projects from the rear surface 24 near one end of plate 12. Said stud has a shank 26 and a peripheral flange 28 which provides the shoulder portion of the stud. A fastening member here shown as a plastic strip 30 of substantial stiffness is removably connected to stud 22 by means of a bayonet slot 34 provided at one end of strip 30. The opposite end of strip 30 is provided with lateral extensions 36 which have bevelled edge portions 38 on their inner surfaces. Lateral projections 36 of fastening member 30 are releasably engaged by retaining members 40 being removably engageable in recesses 42 provided at the inner corners of said members. Ribs 44 and 46 are provided on the end surface of plate 12 and on the upper surface of member 30, respectively, said rib 46 being positioned near the laterally projected edge of member 30. Stud 22, retaining members 40 and rib 44 provided on the end surface 24 of plate 12 are all preferably formed of a plastic and can be molded with said plate when the latter is molded or can be formed as separate elements and subsequently secured to said plate.

It will be understood that when lateral projections 36 of member 30 are engaged in recesses 42 of retaining members 40, rib 44 of plate 12 is positioned in front of rib 46 of member 30, as illustrated in Figs. 3 and 5, and releasably prevents movement of member 30 longitudinally of plate 12, lateral movement of member 30 being substantially prevented by the confronting side

edges of retaining members 40. Further, in this connection it will be understood that longitudinal movement of member 30 is releasably prevented by the engagement of the shank 26 of stud 22 in the smaller part of the bayonet slot 34, the flange 28 of said stud overlying the adjacent surface portions of member 30, as illustrated in Fig. 2.

When it is desired to release member 30 from retaining members 40, it is merely necessary to push on the end 48 of said fastening member in a direction toward the opposite end thereof. This pressure results in forcing rib 46, which it will be observed has a rounded outer surface, over rib 44 which has a similar rounded surface, thus moving lateral projections 36 out of recesses 42 and bringing member 30 to the position illustrated in Fig. 4 in which said fastening member is connected to plate 12 only by the engagement of stud 22 in the small end portion of the bayonet slot 34. In this position of fastening member 30 the latter can be swung clear of retaining members 40 about the axis of stud 22 and if desired said retaining member can be completely disconnected from plate 12 by aligning the larger end portion of the bayonet slot 34 with the peripheral shoulder of the stud.

It will of course be understood that the shoulder board is attached to the jacket by passing strip 30 through the conventional loops on the jacket of the uniform and that when it is desired to secure fastening member 30 in retaining members 40, fastening member 30 is positioned as illustrated in Fig. 4, stud 26 engaging in the small end of bayonet slot 34 and rib 46 abutting rib 44. When the parts are in that position, a pressure exerted on the end 50 of fastening member 30 toward the opposite end 48 thereof and downwardly toward the surface 24 of plate 12 results in rib 46 snapping over rib 40 and in the projection of bevelled edges 38 into recesses 42.

From the above description, it will be apparent that the construction embodying the present invention is well adapted to accomplish the several objects thereof. Also, it will be noted that the shoulder board embodying the present invention is of light weight and yet possesses the proper degree of stiffness. Also, it will be noted that there is no fabric which might become worn or frayed and that the stiffness of plate 12 is inherent therein and is not formed as the result of incorporating a separate stiffening element which would require the application of a fabric or other covering layer thereto. Further, it will be noted that since the plate 12 is formed of a plastic it is waterproof and for this additional reason the shoulder board is not subject to impairment by moisture.

While I have shown and described the preferred embodiment of my invention, it will be understood that the latter may be embodied otherwise than as herein shown or described, and that in the illustrated embodiment certain changes in the details of construction may be made without departing from the idea underlying this invention. Accordingly I do not wish to be limited to the construction as specifically shown or described herein except to the extent which may be required by the scope of the appended claims.

Having thus described my invention, what I claim and desire to secure by Letters Patent is:

1. In an article of the kind described, a plate, a shouldered stud carried by said plate at the back thereof, a strip positioned at the back of said plate and extending longitudinally thereof, said strip having a bayonet slot at one end thereof in which said stud is received for removably securing said strip to said plate, laterally spaced retaining members fixed to the back of said plate in positions to engage the other end of said strip, and lateral projections at said other end of the strip releasably engageable by said retaining members, respectively, for releasably securing said other end of said strip.

2. A shoulder board for an officer's uniform, said shoulder board comprising a plate formed of a plastic and comprising the main part of the shoulder board which is exposed to view when said shoulder board is worn on the uniform, a shouldered stud carried by said plate at the back thereof, a substantially non-bendable strip positioned at the back of said plate and extending longitudinally thereof, said strip having a bayonet slot at one end thereof in which said stud is received for removably securing said strip to said plate, laterally spaced retaining members fixed to the back of said plate in positions to engage the other end of said strip, and lateral projections at said other end of the strip releasably engageable by said retaining members, respectively, for releasably securing said other end of said strip.

3. A shoulder board for an officer's uniform, said shoulder board comprising a waterproof homogeneous plate consisting of a solid plastic material, the front surface of said plate constituting the front exposed main surface portions of the shoulder board, a waterproof insignia member denoting the officer's rank carried by said plate on said front surface, said insignia member being also formed of solid plastic material, and means carried by said plate at the back thereof for releasably securing the shoulder board to the shoulder portion of the uniform, said last mentioned means comprising a shouldered stud carried by said plate at the back thereof, a fastening member having a bayonet slot near one end thereof for releasable engagement of said stud therein, whereby to releasably connect said fastening member to said plate at the back thereof, and retaining means on the back of said plate for releasably engaging said fastening member at the opposite end thereof.

4. In an article of the kind described, a plate, a shouldered stud carried by said plate at the back thereof, a strip positioned at the back of said plate and extending longitudinally thereof, said strip having a bayonet slot at one end thereof in which said stud is received for removably securing said strip to said plate, laterally spaced retaining members fixed to the back of said plate in positions to engage the other end of said strip, and lateral projections at said other end of the strip releasably engageable by said retaining members, respectively, for releasably securing said other end of said strip, and interengaging members on said plate and strip for releasably holding said strip against movement longitudinally of said plate, said stud being in the retaining position of said bayonet slot when said last mentioned members are in said strip holding relation.
